GAME OF SKILL

Filed Sept. 22, 1928

INVENTOR.
LOUIS MAASS

BY Rudolph Wildermann
his ATTORNEY.

UNITED STATES PATENT OFFICE

LOUIS MAASS, OF HARTFORD, CONNECTICUT

GAME OF SKILL

Application filed September 22, 1928. Serial No. 307,733.

This invention relates to games in which, for amusement, entertainment or pastime, the player's mental and physical faculties are exercised. A round object is deposited in my machine and by the operation of the player it runs along an edge. Below this edge are various compartments and it depends upon the skill of the operator to have the round object roll into one specified compartment.

10 The primary object of my invention is to test the skill and patience of the operator, the object he plays with being returned to him if he shows sufficient skill; but it is retained by the device if he lacks patience and ability.

15 A further object of my invention is to provide a device which may be coupled to automatic apparatus which issues, as an incentive for the player, other objects, if he is skillful, or which retains the deposit if he fails.

20 Another object of my invention is to provide a savings bank for children, entailing fun and play in connection with the depositing of a coin in the savings bank and offering harmless means to solicit deposits from 25 grown-ups. Briefly described, my invention comprises a game of skill in which the player by striking a plunger, may rollably propel a disc, or ball, or other suitable rolling object, along a runway at a specified speed or

30 with a specified force, to a specified point thereon, at which a receiving open compartment is located, into which the rolling object drops from the runway, and through which compartment the object will be automatically returned to the player. If the force used is greater or less than that required to cause the object to roll into the open compartment from which it will be returned to the player, it will drop from the runway into one or another of a series of closed compartments, separated from the open compartments, and from which closed compartments it will not be automatically returned to the player, but can be recovered therefrom only by access to

45 said closed compartments through a normally locked door forming part of the enclosing walls of said closed compartments.

Further objects of my device will become evident by the perusal of the following description of one form of execution of my in-

vention, which is illustrated in the accompanying drawings, in which:

Figure 1 is a partly bi-sected side elevation of the device.

Figure 2 shows the corresponding right 55 hand end of said view, which to the right, B, shows the end view and to the left, A, a sectional view.

Figure 3 is a top view of my device showing the parts on the inside through the glass cover on top.

Figure 4 is a side view of an alternative part.

Similar numerals refer to similar parts throughout, the various views.

My invention is essentially contained in the inclosure 4, the sides of which are bent on the top to form troughs 5, into which slides from one end the glass cover 6 against the wall 7 on the front of the apparatus. There are ears 8 on the top of the sides, in the back, which are connected by a rod 9. Onto this rod is hinged the door 10, which serves to close the back of the inclosure 4. There is a ridge 11 on the inside of the box, which serves as a stop for the door when it is closed and over which snaps the lock 12, forming part of said door. The lock is operated by a key which fits the key-hole 13.

To the right end of the inclosure is attached the pocket 14, which has an opening 15 on the top, through which is inserted the round object 16. The bottom of this pocket is slightly slanted upwards towards the inclosure and connects, through an opening 17, into the inclosure, that opening allowing the passage of the round object.

To the opposite end of the pocket 14 is attached a hollow hub 18 in which slides the plunger 19, with knob 20. The end of the plunger slidably rests in an opening in the wall of the pocket, facing the round object deposited in the pocket, approximately at its center. A collar 21 on the plunger is tensioned against the bottom of the hollow hub by compression spring 22. That spring 22 must be very sensitive to respond to the slightest variation in the touch of the operator. To bring this about more readily, I use the bracket 39 shown in Figure 4, which 100

takes the place of the hollow hub 18 of the other views. In a slot on that hub is mounted the lever 40 fulcrumed at 41 in that bracket. The end 42, of the longer arm of that lever, 5 tensionally rests against shoulder 21, that tension being brought about by a tension spring 43, extending between the short arm 44 of the lever and the lower end of the bracket 39.

In approximate alignment with the bottom 10 of the pocket is mounted, on the inside of the inclosure, the straight edge 23. One of its ends is fastened to the front wall of the inclosure, the other end passes over, and is attached to, the wall 24 extending across the inclosure. The straight edge 23 is a runway onto which the rolling objects by which the game is operated are rollably ejected directly from a retaining pocket, and upon which they roll until they drop therefrom, either 15 at the sides or end thereof, and fall into one or another of the compartments provided in the box. This runway is purposely constructed with its surface, ends, and side edges entirely free of flanges or channels intended 20 to guide the rolling object in its travel along the runway. Its surface, ends and side edges being thus entirely unobstructed, the object rolling on the runway will either roll to the free end thereof, and drop therefrom, or will 25 drop from either side edge of the runway, before it has reached the runway end. Wall 24 and a similar wall 25 connect at their lower edge by an inclined bottom piece 26, thus forming a chute, the lower end of which 30 opens through the opening 27 in the side wall of the inclosure.

The trap door 28 is hinged onto a rod 29 extending between the sides of the inclosure. When in horizontal position it closes the space 40 formed by the sides of the inclosure, the wall 25 and the door 10. A very light spring 30, coiled up on the shaft 29, its free end extending below trap door 28, lightly tensions that trap door upwards, the upper edge of the door serving as a stop for the trap door 45 against the wall 25, when the door is in a horizontal position. In other words, the door will swing downward when the slightest pressure is exerted upon it, but it cannot 50 swing above the horizontal level.

Two other trap doors, 31 and 32 are hinged upon rods 33, connecting the front wall of the inclosure to the wall 24. By gravity they normally rest, in an angular position, upon 55 the pins 34 on the front wall of the inclosure and on the wall 24, leaving a slight opening between their free ends, which serves as a passage between the upper part of the inclosure and the part below these trap doors. 60 But when the inclosure is turned up-side-down, the trap doors will fall into a horizontal position, their ends meet, resting upon the lower end of edge 23 which is fastened to the wall; they are also stopped from moving 65 further, since their edges 35 strike the sides,

whereby the upper part of the inclosure is completely separated from the part below these trap doors.

My device functions as follows:

The round object used in my device can 70 have the shape of a disc, as shown, or may have the shape of a ball, in which latter case, of course, the pocket openings will have to be shaped accordingly. When the round object or disc 16 is inserted through the opening 15 on top of my device, it rests in the pocket, against the end of plunger 19. If I push the knob 20 on plunger 19 inward, the disc is pushed out of the pocket, through opening 17, into the inclosure, onto edge 23. If the momentum imparted to the disc is sufficiently large, it will roll along the full length of the edge and, along path 36, will drop into the chute and come out of the box from opening 27. But if the movement imparted to the disc 75 was not sufficient, or was too great, the disc will drop off the edge, on the side, following path 37, or it will jump across the chute, following path 38 and land on trap door 28. If the coin follows the path 37, it will drop 80 down to the bottom of the inclosure through the opening between trap doors 31 and 32. If the coin has fallen onto the trap door 28, its weight will push that door downward and after the coin has slipped off the top of the 85 trap door 28 into the space of the inclosure below, the tension of spring 30 will return the trap door 28 into its normal, horizontal position.

It is readily seen that the discs lying on 90 the bottom of the inclosure cannot be removed, except by the opening of the door 10 which is closed by lock 12. If the operator tries to remove discs from the bottom of the inclosure by turning the whole device up-side-down, the trap doors 31 and 32 which then fall into a horizontal position, bottom 26 of the chute and the trap door 28 in the rear compartment will prevent any disc 95 from passing back into the space above.

Many variations in the construction of the receiving pocket, the means of removing the round object from the receiving pocket, the inclosure, the straight edge, the chute, and the various trap doors suggest themselves. 105 They are known to those acquainted with the arts involved in the construction of my device, and they may be adopted according to the use to which I want to put my invention. So for instance, trap doors 31 and 32 may be 110 solid partitions, mounted in the position shown in the drawings, firmly affixed to the adjoining walls, leaving the slot in between. It will be difficult even in that case to shake, or otherwise cause the round objects to pass 115 from the space below these partitions into the space above. The door may be on any of the three sides, or on the bottom of the inclosure. The protection I desire to obtain is therefore not limited to the precise design 120

shown, but it includes any devices involving the principles of my improvements outlined in the following claims:

1. In a game of skill operated by rolling objects, the combination of a closed box, an open compartment and a plurality of separated closed compartments within said box, an unobstructed runway extending from the end of said box, and spanning lengthwise the top of some of said closed compartments, said open compartment being arranged at one end of said runway, an outlet in said open compartments discharging to the outside of said box, an opening in said box at the end of said runway adjacent said box end to accommodate the passage of said rolling objects therethrough, and spring restrained pressure actuated means, to rollably impel said rolling objects through said last mentioned opening and along said runway and into any of said compartments.

2. In a game of skill operated by rolling objects, the combination of a closed box, an open compartment and a plurality of separated closed compartments within said box, an unobstructed runway extending from the end of said box, and spanning lengthwise the top of some of said closed compartments, said open compartment being arranged at one end of said runway, an outlet in said open compartment discharging to the outside of said box, a pocket on said box to receive said rolling objects, an opening in said box connecting the end of said runway adjacent said box end with said pocket, and means in said pocket to rollably eject said objects from said pocket through said connecting opening, and rollably impel them along said runway into any of said compartments.

3. In a game of skill operated by rolling objects, the combination of a closed box, an open compartment and a plurality of separated closed compartments within said box, a narrow unobstructed runway extending from the end of said box, and spanning lengthwise the top of some of said closed compartments, said open compartment being arranged at one end of said runway, an outlet in said open compartment discharging to the outside of said box, a chute in said open compartment connected to said outlet, a pocket on said box adjacent the end of said runway adjacent said box end to receive said rolling objects, an opening in said box connecting said end of said runway adjacent said box with said pocket, and means in said pocket to rollably eject said objects from said pocket through said connecting opening and rollably impel them along said runway into any of said compartments.

4. In a game of skill operated by rolling objects, the combination of a closed box, an open compartment and a plurality of separated closed compartments within said box,

means within said box to connect said closed compartments, a narrow unobstructed runway extending from the end of said box, and spanning lengthwise the top of some of said closed compartments, said open compartment being arranged at one end of said runway, an outlet in said open compartment discharging to the outside of said box, a chute in said open compartment connected to said outlet, a pocket on one of the outer faces of said box adjacent the end of said runway adjacent said box face to receive said rolling objects, an opening in said box face connecting said end of said runway adjacent said box face with said pocket; and means in said pocket to rollably eject said objects from said pocket through said connecting opening and rollably impel them along said runway into any of said compartments.

5. In a game of skill operated by rolling objects, the combination of a closed box having a transparent top, an open compartment and a plurality of separated closed compartments within said box, an unobstructed runway extending from the end of said box, and spanning lengthwise the top of some of said closed compartments, said open compartment being arranged at one end of said runway, shutters providing a closure for the top of said compartments spanned by said runway, an outlet in said open compartment discharging to the outside of said box, a pocket on said box to receive said rolling objects, an opening in said box connecting the end of said runway adjacent said box end with said pocket, and spring restrained pressure actuated means in said pocket to rollably eject said objects from said pocket through said connecting opening and rollably impel them along said runway into any of said compartments.

6. In a game of skill operated by rolling objects, the combination of a closed box having a transparent top, an open compartment and a plurality of separated closed compartments within said box, an unobstructed runway extending from the end of said box, and spanning lengthwise the top of some of said closed compartments, said open compartment, being arranged at one end of said runway and other of said closed compartments not spanned by said runway being arranged adjacent but beyond said open compartment, normally open gravity operated shutters providing a closure for the top of said compartments spanned by said runway, normally closed weight operated shutters providing a closure for said closed compartments not spanned by said runway, an outlet in said open compartment discharging to the outside of said box, a pocket on said box to receive said rolling objects, an opening in said box connecting the end of said runway adjacent said box end with said pocket, spring restrained pressure actuated means in

said pocket to rollably eject said objects from said pocket through said connecting opening and rollably impel them along said runway into any of said compartments, and a door in said box providing access to all of said closed compartments.

7. In a game of skill operated by rolling objects, the combination of a closed box, an open compartment and a plurality of separated closed compartments within said box, an unobstructed runway extending from the end of said box, and spanning lengthwise the top of some of said compartments, said open compartment being arranged at one end of said runway and other of said closed compartments not spanned by said runway being arranged adjacent but beyond said open compartment, lids normally closing the top of the latter mentioned closed compartments, an opening in the top of said closed compartments spanned by said runway, an outlet in said open compartments discharging to the outside of said box, a pocket on said box to receive said rolling objects, an opening in said box connecting the end of said runway adjacent said box end with said pocket, spring restrained pressure actuated means in said pocket to rollably eject said objects from said pocket through said connecting opening and rollably impel them along said runway into any of said compartments.

8. In a game of skill operated by rolling objects, the combination of a closed box, an open compartment and a plurality of separated closed compartments within said box, an unobstructed runway extending from the end of said box, and spanning lengthwise the top of some of said closed compartments, said open compartment being arranged at one end of said runway and not spanned thereby and other of said closed compartments not spanned by said runway being arranged adjacent said open compartment but separated thereby from said spanned closed compartments, an outlet in said open compartment discharging to the outside of said box, a chute in said open compartment connected to said outlet, a pocket on said box to receive said rolling objects, an opening in said pocket for introducing said objects into said pocket, a bottom in said pocket slanting downwardly as it recedes from said box, an opening in said box connecting the end of said runway adjacent said box end with said pocket and adapted to permit the passage of said objects therethrough, and a spring restrained pressure actuated plunger in said pocket arranged to rollably eject said objects from said pocket through said connecting opening and rollably impel them along said runway into any of said compartments.

9. In a game of skill operated by rolling objects, the combination of a closed box, an open compartment and a plurality of separated closed compartments arranged length-

wise of and within said box in alternate order, one of said closed compartments being positioned at one end of said box, a narrow unobstructed runway spanning lengthwise the top of said closed compartment and extending from said end of said box to but terminating at said adjacent open compartment, an outlet in said open compartment discharging to the outside of said box, an opening in said box at the end of said runway adjacent said box end adapted to accommodate the passage of said rolling objects therethrough, and spring restrained pressure actuated means to rollably impel said rolling objects through said last mentioned opening and along said runway and into any of said compartments.

10. In a game of skill operated by rolling objects, the combination of a closed box, an open compartment and a plurality of separated closed compartments arranged lengthwise of and within said box in alternate order, one of said closed compartments being positioned at one end of said box, another of said closed compartments being positioned at the opposite end of said box, said open compartment being positioned between the opposite ends of said closed compartments and adjacent the end of said first mentioned closed compartment, a narrow unobstructed runway spanning lengthwise the top of said first mentioned closed compartment and extending from said end of said box adjacent said closed compartment to but terminating at said adjacent open compartment, an outlet in said open compartment discharging to the outside of said box, an opening in said box at the end of the said runway adjacent said box end adapted to accommodate the passage of said rolling objects therethrough, and spring restrained pressure actuated means to rollably impel said rolling objects through said last mentioned opening and along said runway and into any of said compartments.

Signed at Hartford in the county of Hartford and State of Connecticut this 14th day of September A. D. 1928.

LOUIS MAASS.
